UNITED STATES PATENT OFFICE.

WALTER C. KIESEL, OF COLLEGE PARK, MARYLAND, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,330,474.

Specification of Letters Patent. Patented Feb. 10, 1920.

Application filed February 1, 1918. Serial No. 214,889.

To all whom it may concern:

Be it known that I, WALTER C. KIESEL, a citizen of the United States, residing at College Park, in the county of Prince 5 Georges and State of Maryland, have invented certain new and useful Improvements in Telephone-Exchange Systems, of which the following is a full, clear, concise, and exact description.

10 This invention relates to telephone exchange systems, and more particularly to such systems employing manual means for connecting an operator's telephone set with the connecting circuit used for connecting 15 telephone lines for conversation.

The object of this invention is to provide a system of this character in which secrecy of conversation is assured.

In accordance with this invention, if the 20 listening key of a link circuit joining two subscribers' lines is actuated when the receivers of the connected lines are off the switchhooks, a source of tone supply is then connected with the receivers of the two connected 25 telephone lines, whereby the subscribers know that the operator is listening in and is also operatively associated with the operator's receiver so that the operator may be advised that the link circuit, the listening 30 key of which has been actuated, forms part of a talking circuit between two subscribers.

For a more complete understanding of this invention, reference should be had to the 35 following description considered in connection with the accompanying drawing illustrating one embodiment thereof.

There are shown in the drawing two subscribers' lines A and B which terminate at 40 a central office at which is located a cord circuit C for interconnecting the lines. The apparatus, shown within the dotted rectangle X, is common to the cord circuits of an operator's position, it being understood, of course, that, for convenience only, the two 45 line circuits and the one cord circuit are shown, and that many such lines and a plurality of such cord circuits are, in practice, employed.

50 The subscriber A, in initiating a call, removes the receiver from the switchhook, causing the operation of line relay 5, whereupon line lamp 6 is lighted. The operator, observing the lighted condition of the line lamp 6, inserts answering plug 7 into line 55

jack 8 of line A, whereupon the contacts of the jack 8 are opened, disconnecting the line relay from the line. The line relay is thereupon deenergized and the line lamp extinguished. Answering supervisory relay 60 10 is operated upon the insertion of the plug 7 into the jack 8 and in operating prevents the lighting of answering supervisory lamp 11. The operator may thereupon actuate listening key 12 to connect the operator's telephone set with the calling line. The actuation of listening key 12 closes a circuit including the left-hand winding of relay 13, contact 14 of listening key 12, alternate contact of supervisory relay 10, 70 sleeve contacts of the plug 7 and the jack 8 and resistance 15 to ground. Relay 13 is marginal so that it does not close its contact when a circuit through only one of its windings is completed, but when both windings are included in circuit, its contact is closed for purposes which more fully hereinafter appear.

The operator, after being advised that connection is desired with the line of subscriber B, restores the listening key 12 to normal position and inserts calling plug 27 into line jack 28, thereby lighting calling supervisory lamp 29. Subscriber B is signaled by the actuation of a ringing key 30 85 80 which connects a source of ringing current 39 with the called-for line for operating the usual call bell 38. In response to the actuation of the call bell at station B, the receiver is removed from its switchhook, 90 thereby causing the energization of supervisory relay 31, which attracts its armature, opening the circuit of, and extinguishing the calling supervisory lamp 29.

95 While the receivers are off the switchhooks and subscribers A and B are conversing, should the operator actuate listening key 12, the circuit, including the left-hand winding of relay 13, will be closed as before described and there will also be established 100 a circuit for the right-hand winding of this relay 13, including contact 32 of listening key 12, alternate contact of supervisory relay 31, sleeve contacts of the plug 27 and the jack 28, and resistance 33 to ground. 105 Since both windings of relay 13 are now traversed by current, the relay will attract its armature, closing a circuit which includes the contact and winding of a vibrating relay 34 and the tertiary winding of the 110

operator's induction coil 35. As long as the contact of relay 13 is closed, relay 34 will be alternately energized and deenergized, opening and closing its circuit which includes the 5 tertiary winding of the induction coil 35. An alternating current will therefore be induced into the secondary winding of this induction coil, thereby producing a tone in the receiver 36 and, since the secondary 10 winding of the induction coil is bridged across the talking strands of the cord circuit C, this tone will also be produced in the receivers at stations A and B. The tone in the operator's receiver 36 indicates to the 15 operator that a talking connection exists between subscribers A and B and the tone in the subscribers' receivers indicates to them that the operator is attempting to listen-in on the conversation. Therefore, this tone 20 warns the subscribers whenever an operator attempts to listen-in, and also warns the operator that her telephone set is being associated with a busy connection.

What is claimed is:

25 1. A telephone exchange system comprising two telephone lines, a link circuit connecting the lines together, a supervisory relay for each end of the link circuit and controlled over the respective lines, an operator's telephone set, a listening key for connecting the operator's telephone set with the link circuit, a source of tone supply, and a relay responsive to the actuation of the 30 listening key when both supervisory relays 35 are energized to operatively associate the source of tone supply with both telephone lines.

40 2. A telephone exchange system comprising two telephone lines, subscribers' station apparatus, a link circuit connecting the lines together, an operator's telephone set, a listening key for connecting the operator's telephone set with the link circuit, a source of tone supply, a relay for connecting the 45 source of tone supply to the connected telephone lines, and an operating circuit for said relay jointly controlled by apparatus at the substations and the listening key.

3. A telephone exchange system comprising two subscribers' telephone lines, a link circuit connecting the lines together, an operator's telephone set, a listening switch for connecting the operator's telephone set with the link circuit, a source of tone supply, a relay for operatively associating the source 55 of tone supply with the receiver of the operator's telephone set, and an operating circuit for said relay jointly controlled by apparatus at the substations and the listening switch. 60

4. A telephone exchange system comprising two telephone lines, subscribers' substation apparatus including a receiver connected with each line, a link circuit connecting the lines together, an operator's telephone set, a listening switch for connecting the operator's telephone set with the link circuit, a source of tone supply, electromagnetic means to operatively associate the source of tone supply with the receivers of 70 the two lines and with the receiver of the operator's telephone set, and an operating circuit for said relay jointly controlled by apparatus at the substation and the listening switch. 75

5. A telephone exchange system comprising two telephone lines, subscribers' station apparatus including a receiver connected with each line, a link circuit connecting the lines together, an operator's telephone set, 80 a listening key for connecting the operator's telephone set with the link circuit, a source of tone supply, a relay responsive to the actuation of the listening key when the receivers of the two telephone lines are operatively connected therewith to connect the source of tone supply with the connected telephone lines, and means for preventing the operation of said relay in response to the operation of the listening key until the 90 receivers of the two telephone lines are operatively connected.

In witness whereof, I hereunto subscribe my name this 19th day of January A. D., 1918.

WALTER C. KIESEL.
